UNITED STATES PATENT OFFICE.

WISTER P. BOTT, OF HOMER, LOUISIANA, ASSIGNOR OF THREE-FOURTHS TO FRED C. McCLANAHAN, OF HOMER, LOUISIANA.

DISPLAY CASE.

Application filed January 12, 1927. Serial No. 160,686.

This invention relates to floor cases for the display of goods, being particularly designed for exhibiting cigars and smokers' sundries, whereby the customer is enabled to select the 5 particular cigar or other article desired and the dispenser can maintain the case closed except when making a sale. As a result the goods are protected from dust and miscellaneous handling.

10 The invention furthermore provides a display case which is normally closed, yet adapted to be instantly opened to the customer and which automatically closes, thereby guarding against the same being accidentally left open.

15 The invention also aims to provide a display case of the character aforesaid which admits of a broken glass being readily replaced, and in which the operating mechanism is enclosed, so as not to be interfered with when 20 utilizing the available space for storage.

While the drawings illustrate a preferred embodiment of the invention, it is to be understood that in adapting the means to meet specific needs and requirements, the design 25 may be varied and such other changes in the minor details of construction may be resorted to within the scope of the invention as claimed, without departing from the spirit thereof.

For a full understanding of the invention 30 and the merits thereof, reference is to be had to the following description and the drawings hereto attached, in which,—

Figure 1 is a vertical, longitudinal sectional view of a display case embodying the invention, looking towards the front from the rear.

35 Figure 2 is a vertical transverse sectional view on the line 2—2 of Figure 1, looking in the direction of the arrows.

Figure 3 is an enlarged, fragmentary sectional view on the line 3—3 of Figure 2.

40 Figure 4 is an enlarged detail sectional view on the line 4—4 of Figure 2.

Figure 5 is a fragmentary sectional view on the line 5—5 of Figure 2.

45 Figure 6 is a detail sectional view showing more clearly the manner of attaching a flexible element to the movable front glass.

Corresponding and like parts are referred to in the following description and designated in the several views of the drawings by 50 like reference characters.

The display case is of the type designed to rest upon the floor, and comprises a base, and upper and lower sections, the latter being intermediate the base and the upper section

and generally utilized for storage. The upper, or top section is designed solely for display purposes and the top and enclosing walls are usually of glass to admit of ready observance of the goods on display. The 60 floor, or bottom, 10 of the upper section 11 forms the top of the lower section 12, which, as stated, is generally used for storage. The base 13 is hollow and may be of any preferred formation. The front 14 of the display section 11 is movable vertically and is retained in place and directed in its vertical movements by guide grooves 15 formed in the opposing sides of posts 16. The front 14 consists of a glass plate which slides vertically and closes 65 by an upward movement and opens by a downward movement into the lower, or storage, section 12. The opening in the floor or bottom 10, through which the front 14 slides is suitably lined with felt, or other material, 70 to deaden noise and prevent injury to the front. The upper front rail 17 is connected to the cross rails 18 by means of a metal bar 19 attached to the inner side of the rail 17 and having its ends bent and connected to the 75 cross rails. In this manner the rail 17 is reinforced and may be readily removed to admit of the front 14 being easily replaced when required, or for any other purpose. The several rails or bars forming the top frame of the 80 display section 11 are rabbeted, as indicated most clearly in Figure 2, to receive the glass top 20, which is thereby made readily removable. The several longitudinal and cross rails may be connected by means of angle 85 irons, or in any determinate way. The top front rail 17 is grooved in its bottom side to receive the top edge of the front 14, when the latter is closed, and this groove is lined to obviate noise and insure a close joint. The 90 corner or upright posts 16 may have the ends of the longitudinal and cross rails tenoned therein, as indicated most clearly in Figure 4, thereby supplementing the action of the angle iron connection.

The operating mechanism for the vertically movable front 14 includes oppositely disposed levers 21 which are located within the front portion of the lower section 12. The levers 21 extend in opposite directions and normally incline in an upward and outward direction from their inner lower ends, which are pivoted to a bracket 22 secured to the top 100 23 of the base 13. Links 24 connect the upper outer ends of the levers 21 to clips 25 attached 105 to the front 14. The front 14 is held in the closed position by a spring 26 which is attached 110 to the outer end of the upper rail 17 and to the inner end of the lower rail 18.

to the lower portion of the front 14 adjacent opposite ends thereof. A transverse lever 26 is pivotally connected at its rear end to a standard 27 secured to the top 23 of the base 13, and its front end terminates in a cross piece 28 which is connected by links to the inner ends of the levers 21. In this manner both levers 21 are simultaneously actuated. An operating lever 29 is pivoted intermediate its ends to a bracket 30 depending from the part 23 and the rear end of this lever projects through an opening in the rear of the base 13 and terminates in a treadle 31 to receive pressure of the foot. A link 32 connects the front end of the lever 29 with the front portion of the lever 26 and passes through an opening in the part 23. Downward movement of the rear end of the lever 29 effects an upward movement of the front end of the lever 26 and a corresponding movement of the inner ends of the levers 21. As a result, the outer ends of the levers 21 move downwardly and lower the front 14, thereby admitting of a customer having access to the case from the front so as to select and obtain the desired article. In this connection it is observed that the lever 29 may be operated in any preferred way by pneumatic or electrically operated means, which may be controlled by means of a push button, or in any determinate or preferred way. A partition 33 spaced a short distance from the front of the storage section 12 encloses a space in which the levers 21 and counterbalance means are located, thereby preventing interference therewith of articles placed within the section 12. A housing 34 extends over the lever 26 and prevents interference therewith of articles stored within the section 12.

Counterbalancing means are provided for normally holding the front 14 in closed position and these means may include a combination of springs 35 and weights 36. The springs 35 are of the closed coil type, and are connected at their upper ends to the floor 10 and at their lower ends to the respective levers 21. When the upper outer ends of the levers 21 have moved downwardly, the springs 35 are tensioned and operate to close the front 14 when the force exerted to lower the same has been released.

The weights 36 are directed in their vertical movements by guides 37 which are interposed between the parts 10 and 23. One of the guides is attached to the partition 33, as indicated most clearly in Figure 2, and serves as reinforcing means therefor. A flexible element 38 is connected at one end to a weight 36 and its opposite end passes over a guide pulley 39 and is attached to the clip 25, said guide pulley being suspended from the floor 10. As the front 14 lowers the counterweights 36 rise and when the force expended to lower the front 14 is released the weights 36 descend and effect a closing of the front as will be

readily understood. It is observed that either the weights or the springs may suffice to maintain the front 14 in closed position, but by providing both means a closing of the front is assured, as it is not likely that both means would fail to operate at the same time.

Having thus described the invention, I claim:

1. In a display case having a vertically movable front, operating means for the front including levers arranged in a plane parallel with the said front and pivoted adjacent their inner ends and inclining upwardly and outwardly, means connecting the outer ends of said levers with opposite end portions of the front, and an operating lever having connection with the inner ends of the said levers. 75

2. In a display case having a vertically movable front, levers arranged in a plane parallel with the said front and pivoted adjacent their inner ends and inclining upwardly and outwardly, links connecting the outer ends of said levers with opposite end portions of the said front, an operating lever, and means connecting the operating lever with 85 the inner ends of said levers. 85

3. In a display case having a vertically movable front, levers located beneath the floor of the case and inclined upwardly and outwardly from their inner lower ends, means 95 connecting the upper outer ends of the levers with opposite end portions of the movable front, an operating lever arranged beneath the floor of the case and means connecting the operating lever with the inner ends of the 100 before mentioned levers.

4. In a display case having a vertically movable front, clips applied to the lower edge portions of the movable front adjacent its ends, levers arranged below the floor of the 105 case and pivoted upon the base adjacent their inner ends and normally inclining upwardly and outwardly, means connecting the upper outer ends of the levers with the said clips, an operating lever and means connecting the 110 operating lever with the inner lower ends of the before mentioned levers.

5. A display case including a vertically movable front, levers arranged beneath the floor of the case and pivoted upon the base 115 adjacent their inner ends and normally inclining upwardly and outwardly, and having connection at their upper outer ends with the lower portion of the front adjacent the ends thereof, an operating lever having connection 120 with the inner lower ends of the said levers, counterbalancing springs connected with the inclined levers, weights, flexible elements forming connecting means between the weights and the lower portion of the movable front, and guide means for the flexible elements. 125

6. A display case comprising upper and lower sections, the upper section having a vertically movable front, levers located in the 130

- lower section and inclined upwardly and outwardly from their inner lower ends, means connecting the upper ends of the levers with the lower portion of the movable front adjacent the ends thereof, a transversely disposed lever connected to the inner ends of the before mentioned levers, and counterbalancing means for the movable front located within the lower section.
- 10 7. A display case comprising a hollow base, upper and lower sections, the upper section having a vertically movable front, levers
- located within the lower section and having their upper outer ends connected to the lower portion of the movable front adjacent the ends thereof, a transverse lever connected at its front end to the inner lower ends of the before mentioned levers, an operating lever within the hollow base and connected to said cross lever, and counterbalancing means for the said movable front disposed within the said lower section.

In testimony whereof I affix my signature.
WISTER P. BOTT.
